VALVE COOLING MEANS FOR INTERNAL-COMBUSTION ENGINES

August F. W. Helmbold, Augusta, Ga.

Application January 17, 1946, Serial No. 641,792

1 Claim. (Cl. 123—177)

1 My invention relates to valve cooling means for the exhaust valves of internal combustion engines, the primary object in view being to equip the usual internal combustion engines with inexpensive and simply constructed means for causing the in-coming intake gas in the valve chambers to cool the exhaust valves before such gas is ignited.

Other and subordinate objects, also comprehended by my invention, together with the precise nature of my improvements, and the manifold advantages thereof, will be readily understood when the succeeding description and claim are read with reference to the drawings accompanying and forming part of this specification.

In said drawings:

Figure 1 is a view in plan illustrating my invention applied, in a preferred embodiment thereof.

Figure 2 is a view in side elevation.

Figure 3 is a view in vertical section taken on the line 3—3 of Figure 1.

Figure 4 is a view in plan of the deflector baffle.

Figure 5 is a view in side elevation of the same.

Figure 6 is a view in side elevation of the exhaust valve, and

Figure 7 is a view similar to Figure 3 of a modification of the invention.

Referring to the drawings by numerals, and first to Figures 1 to 6 thereof, my invention has been shown therein, in a preferred embodiment thereof, as forming part of the equipment of an internal combustion engine embodying a single cylinder forming block 1 capped by a cylinder head 2 forming with said block 1 the valve chamber 3 opening into a combustion chamber 4. The usual pair of intake and exhaust poppet valves 5, 6 are mounted, as shown, in the block 1 alongside the cylinder 7.

According to my invention, an upstanding, horizontally elongated, and generally rectangular deflector baffle 8 in the form of a fin of uniform height and thickness, preferably, is provided in the valve chamber 3 and on the block 1 between the pair of valves 5, 6 and the combustion chamber 4 to deflect incoming gas, admitted by the intake valve 5, toward and over the exhaust valve 6, when said valve 6 is closed. The baffle deflector 8 may, as shown, be cast with the block 1. As best shown in Figure 1, the deflector baffle 8 extends generally crosswise of both valves 5, 6 and is formed opposite the intake valve 5 with a major portion 9 curved in a long arc away from said intake valve 5, the portion 9 merging with

10 a shorter end portion 10 oppositely curved relative to the portion 9 and terminating close to the perimeter of the exhaust valve 6.

5 In addition to the foregoing, my invention comprehends providing the exhaust valve 6 with upstanding teats 11 tending to facilitate rapid transfer of heat from said valve and thereby contribute toward cooling the same, and which also act as cooling fins on said valve between and around which the cool deflected intake gas may pass.

10 In the modification illustrated in Figure 7, the deflecting baffle 12 depends from the cylinder head 13. Otherwise the construction and arrangement is the same as that previously described.

15 As shown in the drawings, the deflector baffle 8 is spaced slightly from the cylinder head 2, and the deflector baffle 12 is similarly spaced from the block 14. This spacing may be varied, or eliminated, as may be found suitable in different types of internal combustion engines.

20 In the operation of the engine, the cool intake gas admitted by the intake valve 5 into the valve chamber 3 is deflected by the baffle deflector 8 to pass over the closed exhaust valve 6 and between and around the teats 11. Thus the top of the exhaust valve 6 is cooled, the teats 11 tending to transfer heat from said exhaust valve 6 to the cooler intake gas. This cooling of the exhaust valve 6 advantageously supplements the usual cooling of the same through contact with the cooled valve seat.

25 30 35 The foregoing will, it is believed, suffice to impart a clear understanding of my invention, without further explanation.

Manifestly, the invention, as described, is susceptible of modification without departing from the inventive concept, and right is herein reserved to such modifications as fall within the scope of the appended claim.

40 45 50 What I claim is:

In an internal combustion engine embodying a valve chamber having a pair of intake and exhaust poppet valves therein for admitting gas into said chamber and exhausting the same therefrom, respectively, deflecting means in said chamber for causing the gas admitted by said intake valve to pass over said exhaust valve to cool the same, and cooling studs on said exhaust valve through and around which the deflected gas may pass, said deflecting means comprising an elongated deflector baffle extending alongside said pair of valves and comprising a major portion 55 curving part way around the intake valve for

collecting gas and terminating in an oppositely curved minor portion opposite the exhaust valve.

AUGUST F. W. HELMBOLD.
